(57) **CLAIM**

The ornamental design for a cell phone, as shown and described.

DESCRIPTION

FIG. 1 is a front view depicting our ornamental design when open.

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front view when closed;

FIG. 8 is a rear view when closed;

FIG. 9 is a right side view when closed;

FIG. 10 is a left side view when closed;

FIG. 11 is a top plan view when closed;

FIG. 12 is a bottom view when closed;

FIG. 13 is a sectional view along line 13—13 of FIG. 1 of the cell phone of our ornamental design; and,

FIG. 14 is a sectional view along line 14—14 of FIG. 1 of the cell phone of our ornamental design.

The broken line showings of portions of the cell phone throughout the views are for illustrative purposes only and form no part of the claimed design. The uneven, short-dash long-dash lines indicate the boundary of, but form no part of, the claimed design.
